UNITED STATES PATENT OFFICE.

CHARLES L. NEWKIRK AND SCOTT MCGOWAN, OF DAYTON, OHIO, ASSIGNEES TO THE CRAWFORD, McGREGOR AND CANBY COMPANY, OF DAYTON, OHIO, A CORPORATION OF OHIO.

SANDING MACHINE.

Application filed November 27, 1920. Serial No. 426,750.

To all whom it may concern:

Be it known that we, CHARLES L. NEWKIRK and Scott McGOWAN, both citizens of the United States, residing at Dayton, in the county of Montgomery and State of Ohio, have invented certain new and useful Improvements in Sanding Machines, of which the following is a specification.

My invention relates to improvements in rubbing and polishing machines for rods, and is particularly adapted for sanding, rubbing and polishing wooden rods, such as golf club handle shafts, billiard cues, chair stocks, broom handles and other like articles, but may also be employed for finishing or polishing metal articles, especially where in highly polished surfaces are desired, particularly after being plated.

The object of the invention is to simplify the structure as well as the means and mode of operation of such machines whereby they will not only be cheapened in construction, but will be efficient in use, positive in operation, automatic in action, uniform in result, and unlikely to get out of repair.

In the finishing of golf club handle shafts, billiard cues and like articles, it is customary after turning or otherwise shaping the shaft or rod to produce a smooth surface by rubbing it with sand paper, or other abrasives, thereafter applying successive coats of filler material, and shellac, varnish, or other surfacing material, rubbing the surface briskly after each coat, with pumice and oil or other dressing, and finally polishing the finished product by rubbing it dry, or with oil, to frictionally induce a highly polished surface. These operations have usually been performed by hand, and involve great labor and expenditure of muscular effort. Not only is the hand process slow, but the resulting dust is disagreeable and injurious to the workman, which together with excessive muscular effort required makes it difficult to secure and retain competent workmen, to perform the necessary hand operations. It is difficult to secure uniform surfaces by manual operation, since there is a tendency to rub the rod or handle shaft more vigorously at one point than at another, thereby producing flattened or irregular surfaces.

The present invention is designed to overcome these difficulties by providing means for actuating the rod or handle shaft uni-

formly both as to longitudinal and rotary movement, and to apply equal and uniform pressure thruout the entire stroke.

A further object of the invention is to provide means for automatically actuating the rod or handle shaft operated upon thru successive oscillatory steps alternating with its reciprocatory movement, and to insure the successive rubbing or polishing stroke to be effected thru uniform range or extent of travel.

A further object of the invention is to provide means for automatically advancing the abrasive or rubbing material each time the rubbing elements are retracted for the insertion of a new piece of work.

A further object of the invention is to provide such a rubbing and polishing apparatus, wherein suction means may be employed for drawing the resulting dust.

With the above primary and other incidental objects in view as will more fully appear in the specification, the invention consists of the features of construction, the parts and combinations thereof, and the mode of operation or their equivalents as hereinafter described and set forth in the claims.

Referring to the drawings, Fig. 1 is a top plan view of an assembled rubbing machine embodying the present invention. Fig. 2 is a side elevation thereof. Fig. 3 is a detail end view of the rubbing and material feeding apparatus. Fig. 4 is a front elevation of the work engaging or pressure applying jaws. Fig. 5 is a detail view of the intermittently operated work rotating means, disclosed in Figs. 1 and 2. Fig. 6 is a detail view of a modification of this rotating means.

Like parts are indicated by similar characters of reference throughout the several views.

In the preferred, but not necessarily the only embodiment of the invention, as disclosed in the drawings, 1 is a main frame or table, in this instance of wooden construction, upon which the operating parts of the apparatus are mounted. Transversely arranged at one end of the main frame or table is a power shaft 2, carrying at one end a drive pulley 3, and at its opposite end a disc 4 having a wrist or crank pin 5 to which is connected a pitman or connecting rod 6. At its opposite end the pitman or connected

- rod 6 is engaged with a reciprocatory shaft 7, mounted in suitable bearings 8 for both reciprocatory and rotary movement. The connection of the pitman or connecting rod 6 with the reciprocatory shaft 7 is by means of a swivel head 9, in which the shaft 7 is capable of rotary movement independent of the pitman 6. Adjacent to one of the bearings 8 for the reciprocatory shaft 7, there is located a ratchet wheel 10, which is splined upon the shaft 9 for rotary movement therewith, but the shaft is capable of independent reciprocatory movement thru the ratchet wheel 10. This ratchet wheel 10 may be mounted in any suitable manner to permit its rotary movement, but prevent axial movement with the shaft 7. In the present instance, the ratchet wheel has been shown provided with a peripheral groove 11, in which engage fingers or dogs 12, secured to the bearing 8. It is obvious that other methods of mounting this ratchet wheel may be employed. In this instance, the ratchet wheel is provided with serrations, or ratchet teeth upon its lateral face. These serrations or teeth are engaged by a pawl 13, pivotally mounted upon one end of an oscillatory actuating lever 14, which in turn is pivoted to the top of a pedestal 15 carried by the main frame 1. The pawl 13 is actuated by a retracting spring 16 into engagement with the ratchet teeth of the wheel 10 at all times. The opposite end of the actuating lever 14 is engaged by a cam 17, carried upon the drive shaft 2, with which the lever 14 is yielding held in engagement by a retracting spring 18.
- It will be obvious that as the drive shaft 2 is rotated the shaft 7 will be reciprocated to and fro thru the bearings 8, by means of the pitman 6, connected to the wrist pin 5, upon the disc 4 and at each rotation of the drive shaft and consequently each reciprocation of the shaft 7, the cam member 17 will engage the end of the lever 14, to oscillate such actuating lever causing the pawl 13 to advance the ratchet wheel 10 thru a partial rotation thereby rotating the shaft 7 within the bearing 8, and in the swivel head 9, in addition to its reciprocatory movement.
- At its end the reciprocatory shaft 7 carries a chuck or work holder 19, which may be of any suitable or convenient type. The rod or handle shaft 20 operated upon is engaged in this chuck or work holder 19, and is reciprocated and rotated in unison with the shaft 7.
- Adjustably mounted upon the main frame 1, beyond the end of the shaft 7, is a longitudinally adjustable carriage 21, the adjustment of which is effected by an adjusting screw 22. This carriage 21 comprises a frame slidingly mounted upon guides or ways 23, on the frame 1, which are engaged by angle bearings 24, secured to the underside of the carriage, which serve to keep the carriage alined with the main frame, and the guides or bearing 23 thereon. Mounted upon this carriage 21 are one or more work engaging bodies which in this instance are shown as two relatively adjustable jaws 25 and 26. In the present instance two pairs of these work engaging jaws have been shown. It is obvious, however, that more or less of these work engaging members may be employed, depending upon the length of the rod or shaft operated upon, and the effective length of the stroke, of the reciprocating means. In the present instance the lower jaw 25 is stationarily mounted upon the carriage 21, while the upper jaw 26 is pivoted in ears or fingers 27 projecting upwardly from the stationary jaw 25. These relatively adjustable jaws 25 and 26 are provided with registering grooves in their adjacent faces, thru which the rod or handle shaft 20 operated upon extends. These grooves, preferably though not necessarily are padded or provided with some resilient or yielding cushion 28, substantially surrounding the rod or handle shaft 20 enclosed between such jaws. The upper or pivotally mounted jaw 26 is yielding drawn downward by means of L-shaped bars 29, pivoted at 30 on opposite sides of the adjustable jaw member, and extending downwardly below the carriage 21, where the ends of such links or bars 29 are interconnected by a transverse rod 31, to which is connected one end of a helical retracting spring 32, the opposite end of which is connected to the downwardly extending arm 33, carried upon the carriage 21. By this means the springs 32, exert a constant pull upon the upper or adjustable jaw member 26, causing it to bear firmly upon the interposed rod or handle shaft 20, but enabling it to yield against the tension of the spring 32, to compensate for enlargement or variations of diameter of the rod 20. To insure the registry of the jaws 25 and 26 when closed upon the interposed rod or handle shaft 20, and to prevent their lateral displacement, the lower jaw 26 is provided with upward extending guide fingers 34, between which the upper or movable jaw member 25 extends when in closed relation.
- Interposed between the yielding pressure members or jaws 25 and 26, are oppositely disposed sheets of work treating material, such as sand paper, emery cloth, or fabric charged with pumice or oil or other polishing or finishing dressing. Such sheets of material are disposed on opposite sides of the interposed rod or handle shaft 20, with their work engaging faces turned one toward the other, and toward the rod. Such material is firmly pressed upon the work by the pressure of the work engaging jaws, and

conforms to variations of size or diameter thru the yielding of the jaw 25 and the interposed cushions surrounding the rod or shaft within the registering channels or 5 grooves of the engaging members. As the rod or handle shaft is reciprocated to and fro, intermediate such work treating material, such as sand paper or fabric charged with pumice or polishing material, it is rotated thru successive partial rotations, 10 whereby the surface is uniformly treated by being sanded, rubbed or polished according to the material employed.

In applying stain or other liquid polish, a 15 reservoir or container 35 may be mounted upon the carriage 31 as shown in Fig. 3, and a supply conduit 36 provided leading from said reservoir or chamber thru a passage-way 37 in the stationary jaw or work 20 engaging body 25, and discharging thru the cushion within the rod receiving groove of the jaw, which in this instance would be of porous material. There will thus be afforded a constant supply of stain or liquid 25 finishing or polishing material, automatically distributed and applied by rubbing, as the rod or handle shaft is reciprocated thru the relatively movable jaws, and rotated during its reciprocatory movement.

30 To retract the movable pressure member or jaw 26, against the tension of its spring 32, to enable the removal of a finished job and the insertion of a succeeding article to be operated upon, the carriage 21 is provided with uprights or standards 38, in the top of which is journalled a rock shaft 39. The rock shaft 39 carries rock arms 40, one for each pair of work engaging members or jaws. A link 41 connects the movable 40 jaw 26 with the corresponding rock arm 40 upon the shaft 39. The shaft 39 is oscillated by means of a hand lever 42, thereby turning the rock arm 40 upwardly and rearwardly and drawing the adjustable pressure member or jaw 26 rearwardly about its pivotal connection. The rock arm 40 is capable of being moved slightly beyond a dead center, whereby the jaw or pressure member 26 will be held in its retracted 45 position. This enables the work to be conveniently inserted and removed and the sheet of abrasive or polishing material to be adjusted in relation with the work to present unworn surfaces to each succeeding 50 piece of work. For convenience the jaws or pressure members 25 and 26 have been provided with inturned ears or fingers 43, adjacent to their forward or free edges, beneath which the sheets or strips of abrasive 55 or polishing or other work treating material is engaged, whereby such sheets of material are automatically separated, by the retraction of the pressure or jaw member 26, and are held in such separated relation 60 while the rod or shaft is being removed

and a new one replaced between such sheets of material. For ordinary operation, these sheets or strips of work treating material whether of polishing or abrasive character may be manually adjusted as frequently as 70 they may become worn to present unworn surfaces to the work. However, there has been shown in Fig. 3 means for automatically feeding such sheets or strips of abrasive or polishing material. In this view, 75 two rolls 45 and 46 of work treating material have been shown mounted in a suitable bracket 47 extending rearwardly from the carriage 21. The material is wound upon such rolls with its abrasive or work 80 engaging surface outwardly, and so positioned in the support 47 that as the sheets are unwound, the work engaging surfaces of the treating material will face one toward the other. The sheets or strips of 85 work treating material pass from the respective rolls 45 and 46 in contact one with the other, thru feeding rolls 48 and 49, journaled in the upright or standards 38 upon the carriage 21. Secured to the trunnion shaft of one of these feed rollers 49 is a ratchet wheel 50. Pivoted upon such trunnion shaft adjacent to the ratchet wheel is an operating lever 51 carrying a pawl 52 engaging with the ratchet wheel 50. This 90 operating lever 51 is interconnected by a link 53 with the adjustable work engaging member 26, whereby at each retraction of the pivoted pressure member 26 under the influence of the link 41 and rock shaft 39, the operating lever 51 will be oscillated thru the link 53 to transmit to the feed roller 49 a partial rotation, whereby the strip of working treating material of abrasive or 95 polishing character will be automatically advanced from the supply rolls 45 and 46 intermediate such feed rolls 48 and 49, and between the pressure members or work engaging members 25 and 26, in relation with which they are guided by the inturned 100 guide fingers 43. Thus at each retraction of the work engaging or pressure applying members to insert a new piece of work, the work treating material is automatically advanced a short length sufficient to present 105 an unworn surface at the point of operation. It will be understood that when the apparatus is employed for applying liquid, 110 finish, stain or polishing material from the reservoir or tank 35, the sheet or strip of 115 work treating material will be disconnected, and vice versa.

In Fig. 6 there is shown a modification of the work oscillating means wherein in lieu of the long actuating lever 14, there is 120 employed a short lever 55, mounted upon a suitable bracket 56 secured to the main frame, and carrying at its upper end a pawl 57 engaging a series of ratchet teeth in the periphery of the ratchet wheel 10'. The 125 130

lower end of the actuating lever 55 is extended laterally into the path of a cone shaped head 58, carried by the reciprocatory shaft 7. As the shaft 7 approaches the forward limit of its stroke, the cone shaped cam head 58 engages the lateral extension of the arm 55, thereby oscillating such arm about its pivotal connection, with the bracket 56 and causing the pawl 57 to advance the ratchet wheel thru a partial rotation. To support the extremity of the actuating lever 14, and prevent undue vibration, the end of the lever is preferably though not necessarily mounted in a slotted or bifurcated guide head 59, mounted on the frame 1 adjacent to the ratchet wheel 10.

In Fig. 2, there has been shown a suction or exhaust conduit 60, having a plurality of branches 61, provided with intakes 62, adjacent to the point of operation, upon the handle shaft or rod. By inducing a suction draft thru this conduit by means of a suitable fan, all dust and particles removed by the abrasive will be automatically withdrawn, thereby protecting the health and comfort of the workman.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described our invention, we claim:

1. In a machine of the character described, a shaft, means for transmitting to said shaft both reciprocatory and rotary movement, means for engaging the work with said shaft, and a pair of jaws yieldingly engaging the work between which the work is reciprocated and rotated by the actuation of said shaft.

2. In a rod rubbing and polishing machine of the character described, a work engaging member having opposing relatively movable work treating faces engaging the work throughout substantially its entire periphery and compensating by their relative movement for variations of thickness

of the work, means for reciprocating the work to and from in relation with said engaging member and means for transmitting to the work successive partial rotations.

3. In a rod rubbing and polishing machine of the character described, an engaging member for the rod having a variable contractive work treating face surrounding the work, means for effecting a reciprocatory movement of one of said members in an axial direction relative to the rod and means for intermittently rotating one of said members through successive partial rotations.

4. In a rod rubbing and polishing machine of the character described, a main frame, a rotary drive shaft and a reciprocatory shaft mounted thereon at right angles to each other, a crank carried by the drive shaft, a pitman connecting the crank and reciprocatory shaft, a swivel head affording a connection between the pitman and the reciprocatory shaft whereby the said shaft may be rotated independent of its reciprocatory movement, a ratchet wheel splined upon the reciprocatory shaft through which the shaft reciprocates, an actuating pawl engaging the ratchet wheel and means for intermittently actuating the pawl to advance the ratchet wheel and shaft thru successive partial rotations, a work holding chuck carried by the reciprocatory shaft, and work treating means engaging the rod carried in said chuck.

5. In a rod rubbing and polishing machine of the character described, a reciprocatory shaft capable of rotary movement in addition to its reciprocatory movement, means for reciprocating the shaft and means for intermittently oscillating the shaft thru partial rotations, a work engaging body yieldingly surrounding the rod operated upon, one of said members being carried by the reciprocatory shaft and the other being stationarily held.

6. In a rod rubbing and polishing machine of the character described, a work treating body engaging the rod operated upon, and means for rotating and reciprocating one of said members in relation with the other including a reciprocatory shaft, on which one of said members is carried, a ratchet wheel splined upon the shaft for rotary movement therewith but independent of which the shaft reciprocates, an actuating pawl for the ratchet wheel, and means carried upon the shaft for intermittently actuating the pawl.

7. In a rod rubbing and polishing machine of the character described, a work treating body engaging the rod operated upon, and means for intermittently rotating one of said members and means for reciprocating one of said members intermediate the operation of said rotating means

- including a reciprocatory shaft on which one of said members is carried, a ratchet wheel splined upon the shaft for rotary movement therewith but independent of which the shaft reciprocates, a pawl engaging the ratchet wheel, an actuating lever by which the pawl is carried and a cam member moving in unison with the reciprocatory shaft engaging the actuating lever at a predetermined point in the path of travel of the reciprocatory shaft to effect a partial rotation of the shaft by means of said pawl and ratchet wheel.
8. In a rod rubbing and polishing machine of the character described, a work treating body yeldingly surrounding the rod operated upon, and means for rotating and reciprocating one of said members in relation with the other including, a reciprocatory shaft upon which one of said members is carried, and means for oscillating the shaft and reciprocating the shaft intermediate such oscillations.
9. In a rod rubbing and polishing machine of the character described, a work support capable of transmitting to the rod operated upon both reciprocatory and oscillatory movement, a pair of relatively movable jaws yeldingly actuated one toward the other, between which the rod is moved, said jaws having facings of work treating material.
10. In a rod rubbing and polishing machine of the character described, a work support capable of transmitting to the rod operated upon both reciprocatory and oscillatory movement, and a stationary work engaging body surrounding the rod and having a work treating inner face.
11. In a rod rubbing and polishing machine of the character described, a work support capable of transmitting to the rod operated upon both reciprocatory and oscillatory movement, and a yielding work engaging body surrounding the rod and having a work treating inner face, said body being adapted to yield to irregularities in the surface of the rod.
12. In a rod rubbing and polishing machine of the character described, a work support capable of transmitting to the rod operated upon both reciprocatory and oscillatory movement, a pair of grooved blocks engaging the rod upon opposite sides and having a work treating face in relation with which the rod is reciprocated and rotated and resilient means tending to press said blocks one toward the other to engage the rod therebetween, against which the blocks are capable of spreading movement to compensate for variations of diameter of the rod.
13. In a rod rubbing and polishing machine of the character described, a work support capable of transmitting to the rod operated upon both reciprocatory and oscillatory movement, a retractable presser member bearing upon said rod, a strip of work treating material interposed between the rod and presser member, and means for automatically advancing the said strip of material by the retraction of the presser member.
14. In a rod rubbing and polishing machine of the character described, a work support capable of transmitting to the rod operated upon both reciprocatory and oscillatory movement, a work engaging body movable into and out of engagement with the rod operated upon, a strip of work treating material interposed between the said engaging body and the rod, and automatically operated feeding means to intermittently present a fresh surface of the work treating material to the rod.
15. In a rod rubbing and polishing machine of the character described, a work support capable of transmitting to the rod operated upon both reciprocatory and oscillatory movement, a supporting carriage adjustable axially in relation with the rod, a work engaging body carried by said carriage and having a work treating face in relation with which the rod is longitudinally and revolubly movable, said work engaging body being adjustable to different points in the range of movement of the rod by the adjustment of said carriage.

In testimony whereof, we have hereunto set our hands this 9th day of November A. D. 1920.
